AUDIO VISUAL DISPLAY CABINET

Edwin R. Wisgin, Mayfield Heights, Ohio, assignor to
Rappaport Exhibits, Inc., Cleveland, Ohio

Filed Oct. 13, 1971, Ser. No. 189,060

Term of patent 14 years

Int. Cl. D16—02

U.S. Cl. D61—1 N

Fig. 1

Fig. 2

Fig. 3

Fig. 4

FIG. 1 is a top plan view of the audio visual display cabinet; showing my new design;

FIG. 2 is a front elevational view;

FIG. 3 is a side elevational view; and

FIG. 4 is a rear elevational view thereof.

I claim:

The ornamental design for an audio visual display cabinet, substantially as shown.
